UNITED STATES PATENT OFFICE.

GEORGE CLEMENTS, OF CHICAGO, ILLINOIS.

VACUUM-CLEANER.

1,129,274.

Specification of Letters Patent. Patented Feb. 23, 1915.

Application filed March 17, 1913. Serial No. 754,707.

To all whom it may concern:

Be it known that I, GEORGE CLEMENTS, a citizen of the United States, residing at Chicago, in the county of Cook and State of Illinois, have invented a certain new and useful Improvement in Vacuum-Cleaners, of which the following is a specification.

My invention relates to improvements in carpet sweepers or vacuum cleaners and has 10 for one object to provide removable means for holding the vacuum cleaner nozzle slightly above the floor level, in order that it may not bury itself in long napped rugs and thereby both impede the progress of the 15 air and the progress of the machine.

It is illustrated in one form in the accompanying drawings, wherein—

Figure 1 shows a side elevation of the machine; Fig. 2, a bottom plan view; Fig. 3, 20 a section along line 3—3 of Fig. 2; and Fig. 4, a bottom plan view of a modified form.

Like parts are indicated by the same letters throughout the several figures.

25 The pump chamber A carries at its top the motor housing A¹ in which is contained a motor not shown driving a pump or fan in the chamber A also not shown. The pump or fan discharges into a bag or dust receptacle A² which is removably supported in a clip A³ on the handle A⁴. The handle A⁴ is provided at its lower end with a fork A⁵ pivoted at either side to the housing or chamber A. The lugs A⁶ limit the rotation 35 of the housing with respect to the handle. Electricity to drive the motor is carried through the cable A⁷ from the switch A⁸ to the motor. The cable A⁹ leads to any suitable source of power.

40 The housing A has located at its bottom the suction or vacuum or nozzle chamber B which communicates with the suction nozzle B¹ and also communicates through the ports B² with the interior of the fan chamber. 45 The cap B³ closes the opening B⁴ in the bottom of the suction chamber.

Arranged about the opening B⁴ and concentric with it but slightly removed therefrom is a curved ridge C which ridge is of 50 slightly greater radius of curvature than the largest radius of the cap B³. The curved, substantially semicircular wire member C¹ is adapted to rest against the ridge C and be clamped between it and the bottom of the 55 part B by the edge of the cap B³. This

comprising a cap screw-threaded in the ing arms C² carrying rollers C³ which rollers when in the position indicated in Figs. 1, 2 and 3 project slightly below the nozzle B¹ and together with the caster C⁴ support 60 the device, and allow it to roll along the ground. It will be noted that owing to the curved cross section of the arms and semicircular portion a maximum degree of 65 strength is had. The pressure of the cap effectually clamps the semicircular member against the curved ridge and bottom of the housing so as to hold it rigidly in position.

In the modified form shown in Fig. 4, a broader nozzle D is used. This nozzle contains the usual type of brush D¹ and owing to the breadth of the nozzle the ridge C is dispensed with. The rear edge of the nozzle is recessed at D². A semicircular portion of the roller supporting frame is placed in position surrounding the aperture B⁴. The cap is screwed in position and the roller supporting frame is then clamped between the cap and the nozzle at D², the elbows D³ being also pressed against the edge of the 70 nozzle to hold the frame rigidly in position. It will be noted that the frames used in Figs. 1, 2, 3 and 4 are identical, but where the nozzle is removed from the opening it is necessary to use the curved ridge. Where the 75 nozzle is adjacent the opening the curved ridge may be dispensed with, and the nozzle itself serves as a back for the frame to which the nozzle may be clamped by the cap, and when the operator wishes to use his 80 vacuum cleaner under such circumstances as above suggested where the nap of the rug is long and especially where the nozzle ought not to come into contact with the surface, he merely removes the cap, places the frame in 85 position and tightening the cap clamps the frame in fixed relation to the housing, thus providing a light, conveniently removable, fixed and sufficiently rigid, auxiliary roller or wheel support for the cleaner housing. 90 95 100

It will be evident that while I have shown in my drawing an operative device, still many changes might be made in size, shape and arrangement of parts without departing materially from the spirit of my invention, and I wish, therefore, that my drawing be regarded as in a sense diagrammatic.

The subject matter contained in this application is illustrated in its entirety or in part in each of my co-pending applications, 105 110

Nos. 705,398, filed June 24, 1912, "vacuum cleaner", and 728,566, filed October 30, 1912, "vacuum cleaner".

The roller support or axle which is made up of the curved wire member C¹ and forwardly extending arms D² bent to form the elbows D³ is in effect the wheel supporting frame or axle.

I claim:-

- 10 1. In a vacuum cleaner the combination with a suction nozzle, of an auxiliary supporting frame removably mounted adjacent the nozzle, ground contacting rollers carried thereby, and means for holding said frame in a position of substantial parallelism with the axis of the nozzle, said means comprising a cap screw-threaded in the vacuum cleaner casing and engaging a portion of said frame.
- 15 2. In a vacuum cleaner the combination with a suction nozzle of an auxiliary supporting frame removably mounted adjacent the nozzle, ground contacting rollers carried thereby and means for holding said frame in a position of substantial parallelism with the axis of the nozzle, said means
- 20 25

comprising a cap screw-threaded in the vacuum cleaner casing and engaging a portion of said frame, the frame being provided with a curved portion adapted to surround said cap, a ridge mounted on the vacuum cleaner and concentric with said cap and in engagement with said curved portion.

3. In a vacuum cleaner the combination with a suction nozzle of an auxiliary supporting frame removably mounted adjacent the nozzle, ground contacting rollers carried thereby and means for holding said frame in a position of substantial parallelism with the axis of the nozzle, said means comprising a cap screw-threaded in the vacuum cleaner casing, a recess in opposition to said cap, said recess and said cap engaging said frame to hold it in position.

In testimony whereof, I affix my signature 45 in the presence of two witnesses this 14th day of March, 1913.

GEORGE CLEMENTS.
